UNITED STATES PATENT OFFICE.

WILLIAM EICHHOLZ, OF CICERO, ILLINOIS, ASSIGNOR TO ILLINOIS ENGINEERING COMPANY, OF CHICAGO, ILLINOIS, A CORPORATION OF ILLINOIS.

HEATING SYSTEM.

Application filed September 5, 1919. Serial No. 321,877.

To all whom it may concern:

Be it known that I, WILLIAM EICHHOLZ, a citizen of the United States, residing in the village of Cicero, county of Cook, and 5 State of Illinois, have invented certain new and useful Improvements in Heating Systems, of which the following is a specification.

This invention relates to heating systems 10 and particularly to apparatus capable of use in systems of the low pressure vapor type.

The objects of the invention are to provide in a system of the character referred 15 to, means for effectively returning the water of condensation to the boiler and particularly relates to novel features of the return tank, wherein all the working parts are enclosed therein, thereby eliminating 20 outside moving parts, and effectively reducing wear and preventing tampering with mechanisms, comprising a float, valve mechanisms, and pivotally mounted weights for operating the valve mechanisms and 25 connections between the pivotally operated float and the valve mechanisms; to provide a construction wherein all of the operating parts are mounted upon a removable cover 30 plate thereby rendering easy access to the several parts for inspection or repairs and in general to provide an economical construction with few moving parts and wherein in positive and accurate action is assured.

In the drawings: 35 Fig. 1 is a side elevation showing part of a heating unit, and return tank.

Fig. 2 is a sectional elevation through the return tank.

Fig. 3 is a cross section through the 40 return tank viewed in the direction of the arrows on line 3-3 of Fig. 2.

Referring to the drawings, 1 designates the boiler and 2 the main steam supply pipe leading to radiators or heating system (not 45 shown). 3 is a return pipe through which the water of condensation passes from the heating system and a branch pipe 4 leading from pipe 3 is provided with a check valve 5 allowing free passage therethrough 50 to an upright pipe 6 through a T connection 7. The pipe 6 is provided with a valve 8 and is connected at its upper end to the return tank 9. Intermediate and connecting the boiler and T 7, is a pipe 55 10 having a valve 11, a branch pipe 12

through which the drip from the steam supply main is returned to the pipe 10 and a check valve 13. Boiler pressure of steam holds the check valve closed until valve actuated mechanisms which will be present- 60 ly described overcomes the same. Referring to the return tank, it is mounted on the upright pipe 6 and is situated between the heating system and the boiler and is connected up with the pipe 4 which is return- 65 ing the water of condensation to the boiler. Within the return tank is pivotally mounted a float 14. This float is above the connection of the pipe 6 and is supported on the rod 15 and casting 16 which casting is 70 loosely mounted on the pivot pin 17, said pivot pin being secured in a strap 18 to a cover 19.

The casting 16 extends upwardly in a V- 75 shape, the arms 20 and 21 of which are de- signed to engage a lug 22 on a weighted cross shaped member 23 loosely mounted on the pivot pin 17 and provided with lugs 24 and 25 adapted to engage the stem 26 of a second weighted member loosely pivoted 80 above the pivot pin 17 at 27 and having an arm 28 adapted to engage adjusting nuts 29 and 30 on a rod 31. The upper end of this rod is pivoted at 32 to a bar 33 pivoted at 34 to a bracket which bracket is bolted or 85 otherwise secured to the cover 19.

To the bar 33 is pivoted at 35 the stem 36 of a valve 37, the seat of which is connected with a vent pipe 44 by means of condenser pipe 38 and pipe 38^a. The condenser pipe 38 is interposed between the vent pipe and the return tank and is nothing more than an enlarged section of the vent pipe. Its function is to condense any water vapor which might find its way out through valve 37, and being inclined toward the return tank, the water of condensation will flow back into the return tank, thereby allowing none to escape from the system. 90 The vent pipe 44 which is connected to the condenser pipe 38 furnishes an outlet for the air in the system when the valve 37 is opened. A special check valve 45 is placed in the vent pipe. This check valve is very 95 sensitive allowing the air to pass from the system but closing when it tends to flow into the system as it does when the system is cooling.

At the opposite end of bar 33 is pivotally 100 secured at 39 the stem 40 of a valve 41, the 105

seat of which is connected to a steam pipe 42, which steam pipe is connected with the main steam supply pipe 2 and is provided with a valve 43.

- 5 In operation it will be noticed that as the water of condensation rises in the supply tank or discharged therefrom, the float will cause the V-shaped casting to engage the lug 22 on the cross-shaped weighted member 23
10 and as it advances, the weighted member will be carried to a point beyond the center of gravity at which point the weighted member will be free to fall and cause either the lug 24 or 25 to strike the stem of the
15 weighted member 26, giving it a hammer-like blow which will, through arm 28 adjusting nuts 30 or 29, operate the rod 31 and cause a quick release of and closure of either the steam valve or vent valve as the case
20 may be.

The water of condensation having caused the reversal of the valves 37 and 41 as shown in Fig. 2, the admission of steam plus the water pressure in the supply tank
25 will overcome the check valve 13 and allow the water of condensation to pass the check valve and enter the boiler.

When the water of condensation has passed from the return tank to the boiler
30 the float 14 will again resume its position shown in Fig. 2, and the steam valve 41 will close while the valve 37 to the vent pipe will open, thereby allowing any steam vapor that might remain in the return tank to be
35 condensed in condenser pipe 38 and flow back into the return tank and also allowing the air from the system and tank to escape through vent pipe 44 and check valve 45.

I do not wish to limit myself to the precise details of construction as shown in the drawings.

I claim as my invention:

1. In a heating system, the combination with a return tank, of a pipe for returning the water of condensation to said tank, a check valve for said pipe, a pipe connecting the return water pipe to the boiler, a check valve in the said boiler pipe connection, a pipe connecting the return tank to the main steam supply pipe, a valve in said pipe, a vent pipe connected to the return tank with a condenser pipe interposed therein, and arranged to return water of condensation, a valve in the condenser pipe, a
50 pivoted float in the return tank and actuating means whereby the float causes simultaneously a reversal of the valves in the steam pipe and vent pipe.

2. In a heating system of the character described, the combination with a return tank having a float therein, of a pipe through which water of condensation is admitted thereto, a check valve to prevent back pressure of the water of condensation,
60 a pipe connecting the water of condensation

70 pipe to the boiler, a check valve in said pipe, said check valve being normally held closed by boiler steam pressure, a pipe connecting the return tank to the main steam supply pipe, a valve in said pipe, a vent pipe connected to the return tank with a condenser pipe interposed therein, and arranged to return water of condensation, a valve in the condenser pipe and automatically actuated mechanisms mounted in the return tank whereby the float causes the mechanisms to simultaneously reverse the valves in the vent pipe and steam pipe.

3. In a heating system of the character described the combination with a return tank having a pivoted float therein, of upstanding weighted members one of said members pivoted at the float pivot, and the pivot of the other offset therefrom, connections between the float and one of said weighted members, vent and steam valves connected with the other weighted members and operable connections between the float and the separately pivoted members whereby the inlet and outflow of the water
85 condensate is regulated.

4. In a heating system of the character described, the combination with a return tank having an actuating mechanism comprising upstanding weighted members separately pivoted in offset relation, vent and steam valves connected to one of said weighted members, a pivoted float connected to the other weighted member, connections between the members whereby the actuating
95 mechanism of one of said members serves to actuate the other member and its attendant mechanism.

5. In an apparatus of the character described, the combination with a return tank having automatically synchronized steam and vent valves, of a stand-pipe connected to said tank, a pivoted float mounted in said tank, an upstanding weighted arm connected to the float, and a separate arm pivotally mounted in offset relation, actuating mechanism functioning steam and vent valves connected to the offset arm whereby the functioning of one arm serves to actuate the other arm and its attendant mechanism.

6. In a heating system of the character described, the combination with a return tank having a pivoted float therein, of an upstanding weighted member rotatably mounted on the float pivot and a similar member pivoted in an offset position, a member rigidly fixed to the float member and functioning to limit the travel of one of said weighted members, steam and vent valves functioning with the rotative movement of the offset pivot member and operable connections between the pivoted members whereby a definite functioning of the steam and vent valves accompanies the rise and fall of the water of condensation in the tank.

7. In a heating system of the character

described, the combination with a return tank having a float therein, of a pipe through which water of condensation is admitted thereto, a check valve to prevent back pressure of the water of condensation, 5 a pipe connecting the water of condensation pipe to the boiler, a check valve in said pipe, said check valve being normally held closed by boiler steam pressure, a pipe connecting 10 the return tank to the main steam supply pipe, a valve in said pipe, a vent pipe connected to the return tank with a condenser pipe interposed therein, and arranged to return water of condensation, and a valve in the condenser pipe and automatically 15 actuated mechanisms whereby the float causes the mechanisms to simultaneously reverse the valves in the vent pipe and steam pipe.

WILLIAM EICHHOLZ.
